UNITED STATES PATENT OFFICE.

CHARLES L. TALBOT, OF CHICAGO, ILLINOIS.

LOADING APPLIANCE.

Application filed November 10, 1921. Serial No. 514,125.

To all whom it may concern:

Be it known that I, CHARLES L. TALBOT, a citizen of the United States, residing at Chicago, in the county of Cook and State 5 of Illinois, have invented certain new and useful Improvements in Loading Appliances, of which the following is a specification.

My invention relates to street cleaning 10 and other similar appliances and concerns more particularly an improved and novel style of apparatus for removing snow and the like from the street and loading it upon a truck to be carried away for disposal.

The new structure is intended to provide 15 a complete snow handling machine, but its essential parts may be made as an accessory for street cleaners which remove the ordinary dirt and filth from the pavements, thus giving to such cleaners a capacity for operating efficiently throughout the entire year.

The prime purpose and leading object of 20 my invention is the provision of such a structure which is simple in construction, 25 which operates efficiently, which is unlikely to become injured or damaged in ordinary service, which is easily operated and controlled, and which may be produced and maintained in proper condition at relatively 30 small expense.

To the attainment of this and other desirable ends, the scoop associated with the elevating conveyor is located at the front 35 end of the motor driven vehicle whereby the appliance may be driven over a pavement and remove the snow ahead of it and whereby it may be readily brought to a pile of snow and cause the latter to be removed, elevated, and delivered into a waiting truck.

It is not necessary that the truck back 40 up to the snow loader, but rather it may be drawn up to the side of the latter and receive its load; in fact, the loader is designed to deliver the snow to either side thereof thus permitting the loading of trucks from 45 both sides.

In order that those skilled in this art 50 may have a full and complete understanding of the invention and its several advantages, in the accompanying drawings forming a part of this specification I have illustrated a preferred embodiment of such invention and like reference characters have been used throughout the several views to 55 apply to the same parts of the mechanism.

In these drawings;

Figure 1 is a side elevation of the complete structure;

Figure 2 is a plan view of the same;

Figure 3 is an enlarged vertical section 60 on line 3—3 of Figure 1;

Figure 4 is a fragmentary detail of a portion of the transverse conveyor;

Figures 5, 6, and 7 are details of the elevating conveyor; and 65

Figures 8 and 9 are details of the structure for adjusting the cross conveyor to cause it to be operative at either side of the appliance.

It is intended, although the invention is 70 not so limited or restricted, to use a street cleaner of substantially the type and style set forth in United States Patent 1,239,293, J. M. Murphy, Street Sweeping Machine, granted September 4, 1917 and to so modify 75 it or remove some of its parts whereby it may receive and operate the snow handling attachment or accessory.

Accordingly, the appliance of the present 80 application includes a main frame 20, two rubber-tired front carrying wheels 21, 21, a rear similarly tired steering wheel 22, steering mechanism 23, a steering wheel 24, an internal combustion motor 25 associated with the usual gearing contained in a housing or gear box 26, a drive shaft 27 equipped with sprocket-wheels and chains 28 for rotating the drive wheels 21, 21, a seat 29 for the operator, and a dirt receptacle or storage compartment 30 substantially like the corresponding parts of the machine of the 85 patent referred to, the other elements of the street sweeper being removed to accommodate and operate the snow handling structure about to be described in detail. 90

A suitably-shaped, upright frame, denominated as a whole 31, is removably or demountably bolted or otherwise conveniently fastened to the center portion of the main-frame 20, and supported in part by such supplemental or auxiliary frame and in part by the dirt receptacle 30, to which it may be fastened in any convenient manner, there is an inclined frame, characterized 32 as a whole. 95

Frame 32 has upper and lower pairs of inclined tracks 33 and 34, respectively, which support the plurality of rollers or wheels 35 revolvably mounted on the two stretches of endless sprocket chains 36, 37, 110

which at intervals have suitable lugs or ears 38 to which are fastened transverse blades 39, 39 each strengthened and stiffened by a truss-rod 40 appropriately connected to the 5 end portions of the blades and equipped with central struts 41.

At their upper ends these chains encircle sprocket-wheels 42 on a shaft mounted in bearings carried by the frame 31, and at 10 their lower ends near the ground such chains pass around similar spaced sprocket-wheels 43 on a shaft 44 revolubly mounted in a pair of arms 45, 45 fulcrumed on the inclined frame 32 at 46 with weights 47 on 15 their other ends, such construction permitting of an upward movement of the shaft and sprocket-wheels under abnormal conditions hereinafter referred to.

The shaft of the upper sprocket wheels 20 is rotated from the power shaft 27 through suitable sprocket-wheel and chain connections 110 and 111 and an intermediate cross shaft 112.

The sloping lower members 48, 48 of the 25 frame 32 have cross boards 49 secured thereto, and to prevent wear these are covered with sheet-metal 50, the edge portions of which are bent upwardly or flare outwardly at 51 beneath the lower tracks 34 as is 30 indicated in Figure 5.

To confine the snow above such tracks and prevent its spilling, as it is pushed upwardly by the traveling blades 39, opposite metal side plates 52, 52 are fastened to the frame-work, whereby the plates 50 and 51 in combination with the plates 52 conjointly form an inclined or sloping trough for the accommodation of the upwardly traveling snow.

40 At the bottom of the sloping or inclined frame 32 and below the lower end of the bladed sprocket-chains, I provide a hinged scoop 53 having a bottom wall 54 and flaring side walls 55 shown most clearly in 45 Figure 2.

Such scoop or shovel is hinged at 56 on the lower end of the inclined frame and it has two arms 57, 57, one at each side, extended beyond the hinge pins and supplied with 50 adjustable weights 58, 58.

To adjust or govern the position of such scoop or shovel, it is equipped with an outstanding pin 59 just above one arm of a bell-crank 60 fulcrumed at 56, the other arm 55 being connected by a link 61 to another bell-crank 62 pivoted on the frame 32 and connected by a link or rod 63 to an operating or controlling handle or lever 64 fulcrumed on the frame 31 in convenient position to be actuated by the occupant of seat 29.

The scoop normally overbalances the action of the weights and its position can be easily regulated by manual actuation of the 65 handle, any suitable locking means, not

shown, being provided for the latter to hold it in the desired relation.

Thus each blade of the inclined conveyor as it passes down around the lower sprocket-wheels will remove a portion of the contents of the scoop and push it up the inclined trough ahead of it, the position of the whole appliance, and particularly that of the scoop or shovel, being regulated and governed by the operator to enable the 70 blades to efficiently and effectively perform the function specified.

Such blades also may be used to wear away or break down a pile of snow into the scoop 80 from which it is carried up as indicated.

On the frame 31 a cross conveyor is mounted and so constructed that it may deliver its load to either side of the appliance.

Such conveyor or carrier comprises a pair of spaced, endless sprocket-chains 70, 71, 85 passing around sprocket-wheels 72 and 73 mounted on shafts 74 and 75 supported in bearings 76 and 77 on the opposite ends of an adjustable frame 78 adapted to slide during its adjustment crosswise the framework 90 31 on a plurality of anti-friction rollers 79.

The upper stretches of these companion chains are driven by a pair of sprocket-wheels 80, one for each chain, located below the upper portion of the chain as shown in 95 Figure 3, and in cooperative relation therewith, whereby the turning of the sprocket wheels causes the usual travel of the chains in either direction depending upon the control mechanism described below.

To hold such portions of the chains down in proper position with relation to the driving sprocket-wheels, I employ idler rollers 81, 81 supported on the frame 31 as depicted in Figure 3.

The two sprocket wheels 80 are on a suitably-supported shaft 82 equipped with a sprocket-wheel 83 driven by a sprocket-chain 84 operated by a sprocket-wheel 85 on a shaft 86 supplied with a friction cone 87 adapted to be rotated by either one of a pair of similar cones 88 and 89 slidable on and rotated by a shaft 9 driven from the shaft 27 through a sprocket chain 91 coacting with sprocket-wheels on the two shafts 110 115 in the usual way.

The friction cones 88 and 89 are adapted to be slid along on shaft 90 by an enclosing frame 92 operated by a lever handle 93 connected thereto by a link 94.

Thus by means of such controlling handle, the direction of travel of the horizontal chains may be reversed at will.

In order to constitute such chains as a belt conveyor to carry the snow or other material crosswise the machine after receiving it from the elevator, many of the links of the chains are provided with lugs or ears 95 to which the marginal portions of flexible belt 96 are fastened, the lading, of course, being 125 130

supported and transported by the belt proper, the chains on opposite sides thereof constituting the driving means for the belt.

To enable the operator to shift or modify the position of the transverse frame and such belt conveyor carried thereby, to discharge its load at will at either side of the appliance, I provide the following specified cooperating instrumentalities.

10 On the supplemental frame 31, I mount a shaft 100 and equip it with a turn wheel 101 whereby the shaft may be manually operated.

On the shaft I provide a drum 102 associated with two cables 103 and 104 each having an end fastened to the drum and their other ends secured to the opposite end portions of the sliding frame 78, whereby by turning the handle or wheel 101 one cable will be wound up and the other paid out from the drum causing a corresponding sliding movement of the frame and the conveyor which it carries.

Turning the wheel and shaft in the other direction will, of course, cause the sliding of the frame and its conveyer in the opposite direction, thus enabling the operator to deliver the load to either side of the machine as he chooses. If desired, two drums 102 may be employed on the shaft 100 and two sets of cables used, one for each side of the slideable or reciprocatory frame.

In operation the machine is caused to travel along the pavement or it may be advanced to a pile of snow, and in either case the scoop in combination with the blades on the elevator chains causes the upward travel of the snow in the inclined chute, from which it is automatically delivered on to the transverse conveyor apron which transports it sidewise and delivers it over its end into a waiting truck, as indicated conventionally in dotted lines in Figure 3.

The position of the scoop for most effective work is controllable by the handle or lever 64 and the scoop is free to rise if it encounters an obstruction, being automatically returned to adjusted position by reason of the fact that its weight overbalances the action of the weights 58, as soon as this action is permitted.

55 In case any of the blades 39 in traveling around the lower sprocket wheels engage any large hard and resisting object such as a rock or piece of ice, such sprocket-wheels and their mounting yield upwardly by reason of the weighted structure employed and prevent breakage of any of the parts.

It will be seen, therefore, that the application described in detail above and illustrated in the drawings fulfills all of the specified advantages and overcomes a need for an apparatus of the structure and operating in the manner indicated.

65. The invention is not limited and restricted

to the precise and exact details of construction since it may be modified within comparatively wide limits without departure from the heart and essence of the invention and without the sacrifice of any of its substantial benefits and advantages. 70

I claim:

1. In a loading appliance of the character described, the combination of a motor-vehicle, a scoop at the front of said vehicle, an inclined chute associated with and adapted to receive the contents of the scoop, upper and lower sets of sprocket-wheels, sprocket-chains coacting with said sprocket-wheels, blades on said chains adapted to push the load up the chute, means to rotate said sprocket-wheels, tracks supporting the lower stretches of said sprocket-chains whereby to prevent drag of the blades on the chute, a cross conveyor receiving its load from said chute and adapted to deliver it to one side of the vehicle, and means to connect said cross conveyor and said sprocket-wheel rotating means with the driving mechanism of the motor-vehicle.

2. In a loading appliance of the character described, the combination of a frame adapted to be demountably secured on the chassis of a motor-vehicle, a scoop on said frame in front of the vehicle, an endless-conveyor on said frame in association with and adapted to receive the contents of said scoop comprising an inclined chute, upper and lower sets of sprocket-wheels, sprocket-chains coacting with said sprocket-wheels, blades on said chains adapted to push the load up the chute, means to rotate said sprocket-wheels, and tracks supporting the lower stretches of said sprocket-chains whereby to prevent drag of the blades on the chute, a cross conveyor on said frame positioned to receive its load from said first conveyor and adapted to deliver it to one side of the vehicle, and means to connect said conveyors operatively with the driving mechanism of the motor-vehicle.

3. In a loading appliance of the character described, the combination of a frame adapted to be demountably secured on the chassis of a motor-vehicle, a scoop on said frame in front of the vehicle, an endless-conveyor on said frame in association with and adapted to receive the contents of said scoop comprising an inclined chute, upper and lower sets of sprocket-wheels, sprocket-chains co-acting with said sprocket-wheels, blades on said chains adapted to push the load up the chute, means to rotate said sprocket-wheels, and tracks supporting the lower stretches of said sprocket-chains whereby to prevent drag of the blades on the chute, a cross conveyor on said frame positioned to receive its load from said first conveyor and adapted to deliver it to either side of the vehicle, means on said frame to cause said cross conveyor 115 120 125 130

veyor to deliver its load at either side of the vehicle, and means to connect said conveyors operatively with the driving mechanism of the motor-vehicle.

5. 4. In a loading appliance of the character described, the combination of a frame constructed to be demountably secured on the chassis of a motor-vehicle street-sweeper having a dirt storage compartment with a

10 portion of such frame resting on a forwardly sloping wall of said compartment, an elevator conveyor on said frame reaching nearly to the ground in front of the vehicle, a cross conveyor receiving its load from the first conveyor and adapted to deliver it at one side of the vehicle, and means to connect said conveyors operatively with the driving mechanism of the motor-vehicle.

15 5. In a loading appliance of the character described, the combination of a frame constructed to be demountably secured on the chassis of a motor-vehicle street-sweeper having a dirt storage compartment with a portion of such frame resting on a forwardly sloping wall of said compartment, an inclined elevator conveyor on said frame reaching nearly to the ground in front of the vehicle, a cross conveyor receiving its load from the first conveyor and adapted to 20 deliver it at a side of the vehicle, means to connect said conveyors operatively with the driving mechanism of the motor-vehicle, and means on said frame to cause said second conveyor to deliver its load to either side of the vehicle at will.

25 6. In a loading appliance of the character described, the combination of a frame constructed to be demountably secured on the chassis of a motor-vehicle street-sweeper having a dirt storage compartment with a sloping wall with a portion of such frame resting on such sloping wall, a scoop on said frame in front of the vehicle, an endless conveyor on said frame in association with 30 and adapted to receive the contents of said scoop comprising an inclined chute positioned over the sloping wall of said dirt storage compartment, upper and lower sets of sprocket-wheels, sprocket-chains coating with said sprocket-wheels, blades on said chains adapted to push the load up the chute, means to rotate said sprocket-wheels, and tracks supporting the lower stretches of

35 said sprocket-chains whereby to prevent drag of the blades on the chute, a cross conveyor on said frame positioned to receive its load from said first conveyor, means to connect said conveyors operatively with the driving mechanism of the motor-vehicle, and means on said frame to cause said cross conveyor to deliver its load at either side of the vehicle.

40 7. In a loading appliance of the character described, the combination of a motor-vehicle, a hinged automatically-adjustable scoop at the front of the vehicle and an inclined endless conveyor associated with and adapted to receive the contents of such scoop comprising a sloping chute, upper and lower sets of sprocket-wheels, sprocket-chains above said chute cooperating with said sprocket-wheels, blades on said chains adapted to push the load up said chute, means to rotate said sprocket-wheels in a direction to carry the blades downwardly around the 45 lower set of sprocket-wheels toward the scoop, and an automatically adjustable mounting for the lower set of sprocket-wheels whereby the conveyor may yield under abnormal conditions.

50 8. In a loading appliance of the character described, the combination of a motor-vehicle, a hinged automatically adjustable scoop at the front of the vehicle, an inclined endless conveyor associated with and adapted to receive the contents of said scoop comprising a sloping chute, upper and lower sets of sprocket-wheels, sprocket-chains above said chute coating with said sprocket-wheels, blades on said chains adapted to push the load up said chute, means to rotate said sprocket-wheels in a direction to carry the blades downwardly around the lower sprocket-wheels toward the scoop, an automatically adjustable mounting for the lower set of sprocket-wheels whereby the conveyor may yield under abnormal conditions, a cross conveyor receiving its load from the upper end of said first conveyor and adapted to deliver it to one side or the other of the vehicle, means to operate said second conveyor, and means to cause said second conveyor to deliver its load to either side of the vehicle at will.

CHARLES L. TALBOT.
